POCKET SCREW DRIVER

Jon Hedu, Watertown, Conn., assignor to The W. E. Bassett Company, a corporation of Connecticut

Filed May 23, 1966, Ser. No. 2,375

Term of patent 14 years

(Cl. D93—4)

FIG. 1 is a top view of the pocket screw driver of my invention;

FIG. 2 is a bottom view of the article of FIG. 1;

FIG. 3 is a side elevation of the article; and

FIG. 4 is a view similar to FIG. 2 but with a part moved to operating position.

The portions shown in broken lines are for purposes of illustration only.

I claim:

The ornamental design for a pocket screw driver, as shown and described.
